by *Alexander S. Keenan*
His Attorney.

UNITED STATES PATENT OFFICE.

WILLIAM J. KEENAN, OF SCHENECTADY, NEW YORK, ASSIGNOR TO GENERAL ELECTRIC COMPANY, A CORPORATION OF NEW YORK.

ELECTRIC FURNACE.

Application filed February 26, 1927. Serial No. 171,297.

My invention relates to electric furnaces and has for its object the provision of a simple and rugged heating resistor for electric furnaces.

5 In carrying out my invention I provide recesses in the furnace wall in opposite sides of the heating chamber and heating elements consisting of bars extending across the heating chamber and having their ends lying in 10 said recesses. I also provide spacing members for the bars, which members are secured in the recesses and some of which may be electric insulators whereby the bars are 15 connected together into series or parallel relation to form a heating resistor for the furnace.

For a more complete understanding of my invention reference should be had to the accompanying drawing in which Fig. 1 is a 20 fragmentary view in vertical section of an electric furnace embodying my invention; Fig. 2 is a fragmentary sectional view taken along line 2-2 of Fig. 1 looking in the direction of the arrows; while Fig. 3 is a horizontal sectional view on a reduced scale 25 showing the arrangement of the heating resistor.

Referring to the drawing, I have shown my invention in one form as applied to an 30 electric furnace provided with heat refractory walls 10 enclosing a heating chamber 11. This wall may be and preferably is formed of heat refractory bricks. Near the top of the heating chamber specially formed 35 bricks 12, forming supporting members, are secured to the wall at opposite sides of the heating chamber. As shown, these special bricks 12 are built into the wall in two horizontal rows at opposite sides of the heating 40 chamber. Preferably, the two rows are co-extensive with the particular walls in which they are placed, for example, they will extend from the front to the back of the furnace. The bricks are each provided with a 45 recess 13 which in the form shown consists of an inner cylindrical opening 13^a extending horizontally and parallel with the furnace wall and an outer slot 13^b communicating therewith and also extending horizontally, but having a smaller dimension in a 50 vertical direction. The special bricks being placed in end to end relation with their recesses registering thus provide two recesses in opposite walls of the heating chamber.

55 The heating resistor is made up of a plu-

rality of bars 14, made of a suitable resistance heating material, which are shown as being cylindrical in form. These bars are preferably made of a mixture of material comprising a base material of silicon carbide 60 with an inner mixture of graphite, calcium carbide and oxides of iron, such as disclosed, for example, in Patent No. 1,420,980, to Eich-emberger, dated June 27, 1922. The bars have their ends extending into the recesses 65 13 whereby they are supported in the heating chamber. Spacing members 15 for the bars are also provided in the recesses. These spacing members are cylindrical in form so as to loosely fit into the inner portion of the 70 recess 13^a and are provided with grooves at their ends in which the bars are received and secured between two adjacent spacing members. The spacing members also serve the 75 purpose of establishing an electrical connection with the bars. By using spacing members of electrically conducting material, and suitably locating the supply terminals, the bars may be connected in parallel while by 80 using alternate spacing members of insulating material, as shown in the drawing, the bars are connected in series.

In the arrangement shown, with an even 85 number of bars connected in series, the electrical connections for the two ends of the resistor are made on the same side of the furnace. A terminal member 17 is provided at one end of the recess in electrical connection with a conducting spacing member 18. This terminal 17 is provided with a shoulder 90 19 which rests on an insulator 20 surrounding it at the point where it projects from the furnace. At the opposite end of the recess, an electrical connection is made with the end spacing member 2. This spacing 95 member, however, is forced inward by a helical spring 22 whereby the series of bars and the spacing members are secured together and a good electrical contact maintained between them. A terminal 23 is provided having an enlarged inner end in engagement with the spacing member 21 and of substantially the same size as the spacing member. A smaller portion of the terminal extends outward through the helical spring 22 and the spring is seated on the shoulder 24 thereby formed. The outer end of the spring bears against an adjusting nut 25 secured in a bracket 26 whereby the tension 100 of the spring can be adjusted. A central 105 110

bore is provided in the nut 25 for the terminal, this bore being provided with an insulating bushing 27. It will be noted that the outer ends of the spacing members 18 and 21 are convex and fit in the concaved inner ends of the terminals 17 and 23. The pressure applied by the spring 22 forms a good electrical contact at these contacting surfaces as well as between the various spacing members and the resistor bars 14. As shown in Fig. 3, the spacing members on the opposite side of the furnace are held in good electrically conducting relation with the ends of the bars by means of a spring 28.

15 The spacing members may be made of any suitable insulating or conducting materials as the case may be. The conducting spacing members may be made of the same material as the resistor bars but containing a 20 greater amount of iron oxide to increase its conductivity, while the insulating spacing members may be made of an aluminum-oxide composition.

While I have described my invention as 25 embodied in concrete form and as operating in a specific manner in accordance with the provisions of the patent statutes, it should be understood that I do not limit my invention thereto since various modifications 30 thereof will suggest themselves to those skilled in the art without departing from the spirit of my invention the scope of which is set forth in the annexed claims.

What I claim as new and desire to secure 35 by Letters Patent of the United States is:

1. An electric furnace comprising heat refractory walls forming a heating chamber, supporting members provided with recesses secured to said walls on opposite sides of 40 said chamber, bars forming heating elements extending across said heating chamber having their ends lying in said recesses, and electrically conducting spacing members for said bars in said recesses whereby said bars 45 are electrically connected together to form a heating resistor.

2. An electric furnace comprising heat refractory walls forming a heating chamber, supporting members provided with recesses 50 secured to opposite sides of said chamber, bars forming heating elements extending across said heating chamber having their ends lying in said recesses, electrically conducting spacing members for said bars in 55 said recesses whereby said bars are electrically connected together to form a heating resistor, and yieldable means for holding said spacing members and said bars in electrically conducting relation.

3. An electric furnace comprising heat refractory walls forming a heating chamber, supporting members provided with recesses secured to opposite sides of said chamber, bars forming heating elements extending across said heating chamber having their ends extending into said recesses and alternately arranged conducting and insulating spacing members for said bars in said recesses whereby said bars are electrically connected together to form a heating resistor. 70

4. An electric furnace comprising heat refractory walls forming a heating chamber, supporting members secured to said walls on opposite sides of said chamber, bars forming heating elements extending across 75 said chamber having their ends resting on said supporting members, spacing members for said bars on said supporting members, at least part of said spacing members being electrically conducting, and resilient means 80 for holding said spacing members and bars together in good electrically conducting relation.

5. An electric furnace comprising heat refractory walls forming a heating chamber, 85 supporting members secured to said walls on opposite sides of said chamber, said supporting members being provided with recesses, bars of carbonaceous material forming heating elements extending across said 90 chamber having their ends lying in said recesses, spacing members for said bars in said recesses, at least part of said members being electrically conducting, and resilient means 95 for holding said spacing members and bars together in good electrically conducting relation.

6. An electric furnace comprising heat refractory walls forming a heating chamber, heat refractory electrically insulating supporting members built into said walls at opposite sides of said heating chamber, said members being provided with horizontal recesses, bars of carbonaceous material forming heating elements extending across said 105 heating chamber and having their ends lying in said recesses, spacing members for said bars in said recesses, at least part of said spacing members being electrically conducting whereby said bars are connected together to form a heating resistor, and resilient means for holding said spacing members and bars together in good electrically conducting relation. 110

In witness whereof I have hereunto set my 115 hand this 24th day of February 1927.

WILLIAM J. KEENAN.

Certificate of Correction.

Patent No. 1,641,764.

Granted September 6, 1927, to

WILLIAM J. KEENAN.

It is hereby certified that error appears in the printed specification of the above-numbered patent requiring correction as follows: Page 1, line 95, for the numeral "2" read 21; and that the said Letters Patent should be read with this correction therein that the same may conform to the record of the case in the Patent Office.

Signed and sealed this 18th day of October, A. D. 1927.

[SEAL.]

M. J. MOORE,
Acting Commissioner of Patents.
